UNITED STATES PATENT OFFICE.

CARL PFANSTIEHL, OF HIGHLAND PARK, ILLINOIS, ASSIGNOR TO PFANSTIEHL COMPANY, INC., OF NORTH CHICAGO, ILLINOIS, A CORPORATION OF NEW YORK.

POPPET VALVE.

1,423,876.

Specification of Letters Patent. Patented July 25, 1922.

Application filed July 25, 1918. Serial No. 246,633.

To all whom it may concern:

Be it known that I, CARL PFANSTIEHL, a citizen of the United States, residing at Highland Park, in the county of Lake and 5 State of Illinois, have invented a certain new and useful Improvement in Poppet Valves, of which the following is a full, clear, concise, and exact description, reference being had to the accompanying drawings, forming a part of this specification.

This invention relates to poppet valves and is especially concerned with the provision of a poppet valve to be used as an exhaust valve for internal combustion engines.

15 The object of this invention is to provide a poppet valve which may be used as an exhaust valve for internal combustion engines of such a character that it will expand substantially the same amount under operating 20 conditions that the supporting portions of the engine expand under the same conditions, so that it will be unnecessary to provide any loose connections in the operating mechanism of the poppet valve to compensate 25 for the difference in expansion between the valve and the supporting portions of the engine, as it is necessary to do where the valves are constructed of materials which expand different amounts under the conditions under 30 which internal combustion engines ordinarily operate.

In my Patent No. 1,283,287, dated October 29, 1918, I have described and claimed a valve comprising a head of high speed steel 35 and a stem of nickel steel and have stated therein that the purpose of providing the stem of nickel steel is to compensate for the high co-efficient of expansion of the high speed steel head of the valve so that the 40 change in length between the valve seat and the end of the valve stem for the temperature at which the valve head and stem are operated will be exactly the same as that of the cast iron portions of the engine. I have also 45 explained that the proportions of nickel in the alloy forming the stem must be varied for different lengths of valve stems and for different facilities for carrying off the heat from the lower portions of the stem.

50 Since filing the above application I have found that in order to provide valves in which the expansion is of substantially the same amount as that of the supporting portions of the internal combustion engines for

a great many different types of engines it is 55 necessary, in case the entire valve stem is made of a nickel steel alloy, to provide a corresponding number of different steel alloys for the reason that it is necessary to compensate for the different expansion in 60 the valves in each different type of engine. This would require carrying in stock a large number of different nickel steel alloys and is objectionable not only from a financial stand-point, but also because any mistake in 65 selecting the proper steel from a large stock of different steels would result in the production of a valve having the wrong co-efficient of expansion.

In order to overcome this difficulty I propose to construct valves of the type illustrated in the accompanying drawing in which the figure discloses a longitudinal section of my improved valve structure.

In this figure the reference character 1 indicates the head of the valve, which is preferably constructed of high speed steel. The stem of the valve comprises two sections, 2 and 3 respectively. The section 2 is fused to the head 1 preferably by means of the process disclosed in my co-pending application Serial No. 138,780, and section 3 is welded or fused to section 2 in any desired manner. I preferably form section 2 of the valve stem of ordinary low carbon steel and section 3 of 75 nickel steel having a higher percentage of nickel than the stem of the valve disclosed in my Patent No. 1,283,287, above referred to. As stated in the last mentioned application an alloy having any desired co-efficient 80 of expansion ranging from that of low carbon steel to substantially nothing can be produced by alloying it with varying percentages of nickel.

By making the percentage of nickel in section 3 of my improved valve sufficiently high I can make any number of valves for different types of engines having valves provided with valve stems of different length and different facilities for carrying off the heat and 95 at the same time employ but one nickel steel alloy for constructing valves for all these different types of engines. This result is accomplished by changing the lengths of the sections 2 and 3. For instance, if it is desired to produce a valve having a comparatively large expansion section 2 of low speed 100 steel may be made comparatively long and

section 3 of the nickel alloy steel will be made comparatively short, whereas if it is desired to provide a valve which will expand a lesser amount section 2 is made shorter and 5 section 3 longer. In this manner by varying the lengths of the sections 2 and 3 I am able to produce valves having any desired degree of expansion and still employ but two different steels, whereas by constructing the valves 10 in accordance with the method disclosed in my Patent No. 1,283,287, referred to above, it is practically necessary to carry a different steel for manufacturing the valves of each different engine.

15 While I have described my improved valve as comprising a head of high speed steel it is to be understood that my invention is not limited to a valve having a head formed of this material, and it is to be further understood 20 that my invention is not limited to a valve in which the head is fused or welded to the stem nor in which the different sections of the valve stems are made of the alloys referred to, but may be made of different 25 alloys as long as they are correctly pro-

portioned to produce a valve having the desired degree of expansion.

Having thus described my invention, what I claim as new and desire to secure by Letters Patent of the United States is:

30 An exhaust valve for internal combustion engines including a stem having two parts formed of metals having differing coefficients of expansion, the union between the metals being so positioned between the ends 35 of the stem as to provide a total stem expansion which, under the temperature at which the stem operates, substantially equals the expansion of the valve housing under the temperature at which it operates, whereby 40 the clearance between the end of the valve stem and its tappet will not be materially altered through changes in temperature.

In witness whereof, I hereunto subscribe my name this 18 day of July, A. D. 1918.

CARL PFANSTIEHL.
